(57) **CLAIM**

The ornamental design for a recessed fishing rod and beverage holder, as shown and described.

DESCRIPTION

FIG. 1 is a top perspective view of the recessed fishing rod and beverage holder of the instant invention illustrating the device cooperating with a fishing rod;

FIG. 2 is a top perspective view thereof illustrating the device cooperating with a beverage;

FIG. 3 is a right side view thereof, the left side view being a mirror image thereof;

FIG. 4 is a front view thereof;

FIG. 5 is a rear view thereof;

FIG. 6 is a top view thereof; and,

FIG. 7 is a bottom view thereof.

The portions of the Figures shown in broken lines are for illustrative purposes only and form no part of the claimed design.
